(57) **CLAIM**

The ornamental design for the ornamental face of a retaining wall block, as shown and described.

DESCRIPTION

FIG. 1 is a perspective view of an ornamental face of a retaining wall block according to an embodiment of the invention.

FIG. 2 is a top view of an ornamental face of a retaining wall block according to an embodiment of the invention.

FIG. 3 is a bottom view of an ornamental face of a retaining wall block according to an embodiment of the invention.

FIG. 4 is a front view of an ornamental face of a retaining wall block according to an embodiment of the invention.

FIG. 5 is a rear view of an ornamental face of a retaining wall block according to an embodiment of the invention.

FIG. 6 is a side view of a first side of an ornamental face of a retaining wall block according to an embodiment of the invention.

FIG. 7 is a side view of a second side of an ornamental face of a retaining wall block according to an embodiment of the invention.

FIG. 8 is a perspective view of an ornamental face of a retaining wall block according to an embodiment of the invention.

FIG. 9 is a top view of an ornamental face of a retaining wall block according to an embodiment of the invention.

FIG. 10 is a bottom view of an ornamental face of a retaining wall block according to an embodiment of the invention.

FIG. 11 is a front view of an ornamental face of a retaining wall block according to an embodiment of the invention.

FIG. 12 is a rear view of an ornamental face of a retaining wall block according to an embodiment of the invention.

FIG. 13 is a side view of a first side of an ornamental face of a retaining wall block according to an embodiment of the invention; and,

FIG. 14 is a side view of a second side of an ornamental face of a retaining wall block according to an embodiment of the invention.

The broken lines appearing in the figures are not intended to form part of the claimed design and are provided for illustrative purposes only.
